UNITED STATES PATENT OFFICE

2,595,974

PEN CLIP

Clarence F. Norlin, Chicago, Ill.

Application May 14, 1949, Serial No. 93,370

5 Claims. (Cl. 24—11)

1

This invention relates to improvements in retainer clips for fountain pens, mechanical pencils and other instruments usually carried in pockets. Retainer clips now in use largely depend on a spring action in the clip which are either difficult to apply to clothing and cause clothing damage or become unsprung and ineffective. Expensive losses due to clip failures are common. The invention will be described as applied to a pocket pen or the like, although it has wider application.

The present invention has for its particular object the provision of a mechanically actuated clip in the form of a hook lever comprising a clamp that is operable without the use of springs.

Another object is to provide a mechanically actuated clip for both opening the clip for insertion in pockets of clothing, and locking the clip in position.

And a still further object is to provide a clip actuated mechanically by a relative sliding movement of the parts of a compound pen cap.

Other objects and benefits will be disclosed in the following descriptions and drawings in which:

Fig. 1 is a side elevation view of a pen employing my safety clip in open position ready to be inserted in a pocket;

Fig. 2 is a front elevation view of the pen shown in Fig. 1;

Fig. 3 is an enlarged transverse medial section view showing my safety clip in open position;

Fig. 4 is a similar view to Fig. 3 showing the clip in locked position; and

Fig. 5 is a cross section view of the clip as it would appear on the section lines 5—5 of Fig. 4.

Now referring to the drawings, I designate the conventional barrel of a pen by the numeral 10 and my safety clip sleeve by the numeral 11. Now referring to Figs. 3, 4 and 5, the sleeve 11, ordinarily made of plastics, has a cap 12 secured to its top as shown. Over the top 12 is a slidable cover cap member 13 which is secured to the cap 12 by a stud bolt 14 secured in position by a nut 15. On the cap 12 is a pair of ears 16 having a pivot bearing 17 mounting a pen clip in the form of a hook lever 18 providing a clamp to secure the pen to a portion of a wearer's pocket. The hook lever 18 has on its forward clamp arm end a downwardly protruding hook 18-h which is designed to coact with a cavity 11-c in the sleeve 11 to more securely fasten the hook in a fabric pocket. On the opposite end of the lever 18 is a cam projection 18-c which coacts with a cam bridge 13-c which extends across an extension 13-e forming a laterally offset portion on the

2

cover cap 13 to house the hook lever 18 as shown. The hook lever 18-c extends through an aperture or slot 12-a in the cap 12 to coact with the cam bridge 13-c as clearly shown in Fig. 3.

When the cover cap 13 is slidably depressed downwardly as shown in Fig. 4, the extension 13-e will contact the cam surface on the hook lever 18 to force the hook 18-h in close juxtaposition with the cavity 11-c. When the cap 13 is slid upwardly as shown in Fig. 3, the bridge 13-c will contact the cam 18-c on the lever 18 to position the hook 18-h upwardly away from the cavity 11-c to permit the fabric in the pocket to be easily inserted therebetween. The relation of the parts is more clearly explained by the cross section in Fig. 5 and the coaction of the various parts will be readily understood by consideration of this figure in conjunction with Figs. 3 and 4.

From the foregoing descriptions it will be understood and appreciated that when the slidable cover cap 13 is moved longitudinally outwardly, the hook lever 18 with its hook 18-h is removed from the sleeve 11 to permit insertion of the clothing between the hook 18-h and the cavity 11-c. When the cover cap 13 is slid downwardly, the extension 13-e on the cam lever 18 will depress the hook 18-h into close contact with the sleeve 11 in order to effectively lock the clothing between the lever hook 18-h and the cavity 11-c.

Thus I have provided a safety clip which is mechanically actuated without springs to provide easy access of the fabric pocket within the clip and by reverse movement will be locked securely in position and cannot be removed except by sliding the cover cap 13 upwardly. This is practically a one-handed movement of the cap that can be habitually acquired and thus a secure safety clip entirely mechanically actuated and without the use of springs is provided.

Having thus described my invention, I now claim as new:

1. In a retainer clip for pocket devices, a sleeve, a cap upon said sleeve, a locking lever pivoted at an intermediate point to said cap, said lever having a forward hooked end with a cam surface upon its outer surface extending forward from said pivot point, said cap having a slot through which the rear end of said lever projects, said lever having a cam projection upon its rear end, and a slidable cover cap extending over said cap and a portion of said sleeve, said cover cap having means for engaging and depressing the forward end of said locking lever when said cover cap is moved in a forward direction and means for engaging said projecting cam and elevating

the said forward end of said lever when said cover cap is moved in a rearward direction.

2. In a device of the character described, a sleeve member, a thimble-like cap upon one end of said sleeve member, a hook lever clamp pivoted adjacent the said end of said sleeve member, said hook lever clamp having a forwardly extending clamping arm with an outer cam surface and a rearwardly extending arm with an outwardly directed cam and a slidable cover telescoped over said cap and having means for engaging over said clamping arm for depressing the same into clamping relation with a garment when said cover is moved in a forward direction, and means for engaging said cam on said rearwardly extending arm for elevating said clamping arm.

3. In a device of the character described, a sleeve member, a clamping lever pivotally mounted upon said sleeve member, said lever having a forwardly extending clamping arm adapted for clamping said sleeve member to a garment and a rearwardly extending arm having a cam and a cover cap slidably mounted with respect to said sleeve and having means adapted for engaging and depressing said clamping arm when said cover cap is moved in one direction and means for engaging said cam for causing an elevation of said clamping arm when said cover cap is moved in the other direction.

4. In a device of the class described, a sleeve member, a cylindrical support upon said sleeve member and extending rearwardly thereof, a clamping

lever pivoted adjacent the rear end of said sleeve member, said lever having a forwardly extending clamping arm and a rearwardly extending actuating arm and a slidable cover member mounted upon said support and having means for engaging said clamping arm for depressing said lever when said cover member is moved in a forward direction and means for engaging said actuating arm for elevating said clamping arm when said cover member is moved in a rearward direction.

5. In a retainer clip for pocket pencils, a sleeve member, a cylindrical support upon said sleeve member and extending rearwardly thereof, a clamping lever pivotally mounted intermediate its length and adjacent the rear end of said sleeve member, a cover member slidably mounted upon said support and having a laterally offset portion adapted for encompassing a part of said lever and means associated with said offset portion for operating said lever.
